UNITED STATES PATENT OFFICE.

CHARLES H. MYERS, OF LE ROY, ILLINOIS, ASSIGNOR TO NATIONAL HARROW CO., OF LE ROY, ILLINOIS, A CORPORATION OF ILLINOIS.

HARROW ATTACHMENT FOR PLOWS.

No. 928,210.

Specification of Letters Patent.

Patented July 13, 1909.

Application filed April 24, 1909. Serial No. 491,996.

To all whom it may concern:

Be it known that I, CHARLES H. MYERS, of Le Roy, in the county of McLean and State of Illinois, have invented certain new and useful Improvements in Harrow Attachments for Plows; and I do hereby declare the following to be a full, clear, and exact description of the invention, such as will enable others skilled in the art to which it applies to make and use the same.

This invention relates to improvements in harrow attachments for plows,—the object of the invention being to provide simple and efficient means to permit a harrow when connected with a plow structure for breaking the earth thrown up in making the furrows, to yield vertically to overcome obstructions, and to so construct said means that it can be positively operated to manually raise and lower the harrow and retain it normally at any desired adjustment with relation to the ground.

With this object in view the invention consists in certain novel features of construction and combinations of parts as hereinafter set forth and pointed out in the claims.

In the accompanying drawing, Figure 1 is a side elevation of a harrow attachment for plows, embodying my improvements. Fig. 2 is a plan view of the same. Fig. 3 is an enlarged vertical section through the lifting device.

1 represents a side rail of a plow frame and 2 a beam connected with said rail by means 35 of a bracket 3. The bracket 3 comprises two members 4—5 secured respectively to the rail 1 and the beam 2 and adjustably connected together so as to permit horizontal adjustment of the beam 2 and the parts carried thereby.

A bearing sleeve 6 is secured to the rear end of the beam 2 and in this sleeve, an arm 7 at one end of a harrow beam 8 is mounted so as to permit said harrow beam to swing 45 vertically. To the rear end of the harrow beam, a harrow 9 of any preferred form of construction, is secured by means of a suitable clamp 10.

Upon the rear end of the beam 2 and in 50 proximity to the bearing sleeve 6, a vertically disposed toothed segment 11 is secured. A hand-lever 12 is pivotally attached at its lower end to the toothed segment 11 and provided with a suitable detent to engage said toothed segment.

A bifurcated bracket 13 is securely clamped to the harrow beam at a point in comparative close proximity with the connection of said beam to the beam 2. The upper end of the bracket 13 is provided with 60 forwardly projecting lugs 14, between which a lever 15 is pivotally supported between its ends. A rod 16 is secured to the bracket 13, passes freely through an opening at the lower end of the lever 15 and extends some distance forwardly from the same. The free end of the rod 16 is provided with a head 17 and encircling said rod is a spring 18 which bears at one end against the head 17 and at the other end against the lower arm of the 70 lever 15. The upper arm of the lever 15 is connected by means of a link 19 with the hand lever 12 at a point removed a short distance from the pivotal support of said hand lever.

With the construction and arrangement of parts above described, it will be seen that when the hand lever is moved forwardly, motion will be transmitted through the link 19 to the upper arm of the lever 15 and as 80 the lower arm of this lever rests against the bracket 13 at a point below the pivotal support of said lever 15, the harrow beam and the harrow carried thereby will be raised. It is apparent that a rearward 85 movement of the hand lever 12 will permit the lowering of the rear end of the harrow beam and of the harrow carried thereby. It will also be seen that should the harrow meet an obstruction it will be permitted to yield upwardly against the resistance of the spring 18. Such yielding movement of the harrow and its beam will be permitted because of the link connection between the upper end of the lever 15 and the lever 12 and the rearward movement of the upper end of the bracket 13,—the lever 15 being pivotally supported between its ends at the upper end of said bracket and bearing at its lower end (which is free to move in one direction) 90 against the spring.

Having fully described my invention what I claim as new and desire to secure by Letters-Patent, is,—

1. A plow attachment, comprising a beam, means for connecting the same with a plow frame, a harrow beam having a hinge-connection with the rear end of said first mentioned beam, a toothed segment secured to the first mentioned beam, a hand lever provided with 105

110

a detent to engage said toothed segment, a bracket secured to the harrow beam, a lever pivoted between its ends to said bracket, a spring bearing against one arm of said lever, and a link connecting the other arm of said lever with the hand lever.

2. A plow attachment, comprising a supporting beam, means for connecting the same with a plow frame, a harrow beam having 10 hinge-connection with the supporting beam, a toothed segment on the supporting beam, a hand lever provided with a detent to engage said toothed segment, a bracket secured to the harrow beam, a rod projecting 15 forwardly from said bracket and provided at one end with a head, a lever pivoted between its ends to said bracket, a spring on said rod normally pressing the lower arm of said lever against the bracket, and a link

connecting the upper arm of said lever with 20 the hand lever.

3. A plow attachment, comprising a hinged harrow beam, a bracket secured to said beam, a lever pivoted between its ends to said bracket and engaging the bracket 25 below the pivotal support of said lever therein, operating means connected with the upper arm of said lever, and a spring supported by the bracket and pressing the lower arm of said lever toward said bracket. 30

In testimony whereof, I have signed this specification in the presence of two subscribing witnesses.

CHARLES H. MYERS.
